US00D933109S

(12) **United States Design Patent** (10) **Patent No.:** **US D933,109 S**
Cohen et al. (45) **Date of Patent:** **** Oct. 12, 2021**

(54) **FABRIC-MONITORING DEVICE**

(71) Applicant: **Uster Technologies, Ltd.**, Caesarea (IL)

(72) Inventors: **Shmuel Cohen**, Kadima (IL); **Ingo Kiefer**, Klettgau (DE); **Sivakumar Narayanan**, Uster (CH); **Christophe Apotheloz**, Gockhausen (CH); **Afik Shoham**, Haifa (IL)

(73) Assignee: **Uster Technologies AG**, Uster (CH)

(**) Term: **15 Years**

(21) Appl. No.: **29/715,394**

(22) Filed: **Dec. 2, 2019**

(30) **Foreign Application Priority Data**

Jun. 19, 2019 (CH) 144745

(51) LOC (13) Cl. **15-06**

(52) U.S. Cl.

USPC **D15/72**; D15/78

(58) **Field of Classification Search**

USPC D15/66-78; D7/393, 394; D8/300, 303, D8/315, 320

CPC D03J 1/007; D03J 1/24; G01N 21/8983; D06H 3/08; D06H 3/04; D06H 3/02

(57) **CLAIM**

The ornamental design for a fabric-monitoring device, as shown.

DESCRIPTION

FIG. 1 is a top perspective view of a fabric-monitoring device.

FIG. 2 is a left end view of the fabric-monitoring device.

FIG. 3 is a right end view of the fabric-monitoring device.

FIG. 4 is a front view of the fabric-monitoring device.

FIG. 5 is a back view of the fabric-monitoring device.

FIG. 6 is a top view of the fabric-monitoring device.

FIG. 7 is a bottom view of the fabric-monitoring device; and,

FIG. 8 is a bottom perspective view of the fabric-monitoring device.

1 Claim, 4 Drawing Sheets
